UNITED STATES PATENT OFFICE

GEORGE GRAHAM AND ADOLPH C. HELMUS, OF DOUGLASTON, NEW YORK

FABRIC-ROLL HOLDER

Application filed April 21, 1928. Serial No. 271,907.

The present invention relates to improvements in fabric-roll holders, that is to say to forms or frames upon which fabrics are wound for storage purposes.

5 The main object of the invention is to provide a casing-like form or cloth holder provided in one of its ends with an opening through which an envelop, containing samples of the cloth or fabric wound upon the 10 said form, may be inserted into the form to be withdrawn when samples are to be furnished to a purchaser.

Another object of the invention is to generally simplify and improve construction of 15 devices of this type.

A further object of the invention is to provide a form or fabric-holder of the character described which is simple in construction, efficient in operation, durable in use 20 and capable of manufacture on a commercial scale, or in other words, one which is not so difficult to make as to be beyond the reasonable cost of such a contrivance.

With these and other objects in view, which 25 will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within 30 the scope of the the appended claim, without departing from the spirit or sacrificing any of the advantages of the invention.

Two of the many possible embodiments of 35 the invention are illustrated in the accompanying drawings, in which:—

40 Figure 1 is a top plan view, partly in section, of a fabric-holder constructed in accordance with the present invention, part of its covering being broken away in order to show the interior construction; Fig. 2 is an 45 end view thereof; Fig. 3 is a section taken on line 3—3 of Fig. 1; and Fig. 4 is a view similar to the one shown in Fig. 1 of a modified construction.

Referring now first to Figs. 1 to 3, inclusive, of the drawings, it will be noted that the

form or holder comprises an oblong frame, including two longitudinal members 10, which are united intermediate their ends by two transverse members 11. All of these members are, preferably, made of wood. 45 Over adjacent ends of the longitudinal members are fitted transverse end members 12. Each of these end members is in the form of a shell, including an end wall 13 and a continuous side wall 14, into one end of which 50 each longitudinal member 10 is fitted. The elements so far described may be united in any suitable manner, thereby forming an oblong frame. The entire frame is covered with some suitable fabric or paper, denoted 55 by the numeral 15, to give the form or holder a finished appearance. As appears from the foregoing the form or holder constitutes a casing, the longitudinal edges of which are rounded, as indicated at 16 (Fig. 3), to permit of proper winding of the cloth or fabric 60 thereon.

In the end wall 13 of one of the shells is provided an oblong opening 17, through 65 which is adapted to be inserted into the form or holder an envelop containing samples of the goods wound upon the fabric form.

The cloth or fabric may be wound upon 70 and unwound from the form or holder without interfering with the sample containing envelop therein. The cloth bolts are stacked with their openings 17 exposed whereby convenient access may be had to the envelops, so that, when a sample is to be removed from an envelop in any one of the forms or holders, 75 this can be done without removing the bolt of cloth from the stack.

The construction herein described is very 80 simple. It is exceedingly rigid by reason of the fact that the ends of the longitudinal members 10 are inserted into shells which are, preferably, made of metal. It can be conveniently assembled. Preferably, first the wooden elements are united and the metallic shells then attached to the longitudinal frame members. After this the covering 15 is put 85 in place.

The modification illustrated in Fig. 4 of the 90 drawings differs from the one above described only in that the frame is provided with a

cardboard or like covering 18, before the covering 15 is mounted thereon. Otherwise the construction and operation of the elements are the same as those described in connection with Figs. 1 to 3, inclusive, of the drawings.

What we claim is:—

A cloth form in the shape of an oblong casing-like frame comprising two longitudinal frame members, two transverse frame members connecting said longitudinal frame members intermediate their ends, two end members, each of said end members being in the form of a shell including an end wall and a continuous side wall, adjacent ends of said longitudinal frame members being inserted into one of said shells with their end faces abutting against the end wall of said shell and with their end portions fitting against the inner faces of the continuous side wall of said shell, whereby said longitudinal frame members are prevented from spreading, and sheet material covering said frame, the end wall of one of said shells being provided with an oblong opening, substantially as and for the purpose specified.

Signed at New York, in the county of New York, and State of New York, this 16th day of March, A. D. 1928.

GEORGE GRAHAM.
